UNITED STATES PATENT OFFICE.

OTTO KEMPER, OF BLOOMSBURG, PENNSYLVANIA, ASSIGNOR, BY MESNE ASSIGNMENTS, OF ONE-HALF TO J. EDWARD BOONE, OF ALMEDIA, PENNSYLVANIA.

GARMENT-CLASP.

SPECIFICATION forming part of Letters Patent No. 722,308, dated March 10, 1903.

Application filed June 11, 1902. Serial No. 111,189. (No model.)

To all whom it may concern:

Be it known that I, OTTO KEMPER, a citizen of the United States, residing at 316 West Fourth street, Bloomsburg, in the county of 5 Columbia and State of Pennsylvania, have invented new and useful Improvements in Garment-Clasps, of which the following is a specification.

This invention relates to garment-clasps, 10 and has for its object the production of a device of this character especially adapted to be secured to suspender-ends, whereby a garment may be suspended, thereby obviating the necessity of buttons on the garment and 15 loops on the suspender-ends.

A further object of the invention is to provide improved means whereby the clasp may secure a firm grip upon the garment, obviating any liability of the clasp becoming 20 casually detached therefrom.

The invention consists in the novel construction, combination, and arrangement of parts, as will be hereinafter fully described and claimed, and illustrated in the accompanying drawings, in which—

Figure 1 is a perspective view of a device constructed in accordance with my invention, showing it as applied. Fig. 2 is a vertical longitudinal sectional view of the same.

Fig. 3 is a transverse section on the line 3 3 of Fig. 1.

1 and 2 designate clamping-plates curved in a transverse direction, as shown by Fig. 3, the upper ends of which are bent to form 35 hinge-leaves 3, through which passes a bail 4, one of its members forming a pintle 5.

The clamping-plate 1 comprises an elongated body portion 6, having notches 7 running transversely thereof. The said body 40 portion gradually widens, forming a head 8, provided with a struck-up portion 9, serving as a socket.

The arm 2 is elongated and has its lower 45 end bent at a right angle, forming a lip 10 to fit within the socket 9.

11 designates a sliding bail embracing the arms 1 and 2, and has its arms provided near their ends with perforations 12, in which are journaled the laterally-projecting lugs 13

of the cam-lever 14. The said lever is formed 50 of a single piece of metal, one end of which is bent at a right angle, forming a cam 15 to engage one of the notches in the plate 1, and its edge is cut out to conform to the contour of the arm 1. The said cam is provided with 55 the lugs 13 above referred to, which are journaled in the perforation 12 of the bail 11, and the opposite end of said lever is bent upon itself to form a finger-grasp 16.

The utility and operation of the device may 60 be explained as follows: The clasp may be attached to any suitable supporting - strap through the medium of the bail 4, and the clamping-plates placed over the edge of the garment to be supported and secured thereto 65 by the jaws being brought together, forcing the lip 10 and a portion of the garment into the socket 9 by sliding the bail 11 down the arms to the limit of its movement and throwing the cam 15 into engagement with one of 70 the notches in the arm 1.

From the foregoing description, taken in connection with the accompanying, drawings it will be readily seen that I provide a clasp which may be easily attached to a suspending member and held against casual displacement upon a garment, thereby obviating the 75 necessity of buttons upon the garment.

Having described my invention, what I claim is—

1. The combination with a bail, of clamping-plates hinged thereto, one of said plates provided with an enlarged head having a socket, and the other provided with a lip to fit within said socket, and a sliding bail carrying a cam-lever to clamp said plates.

2. The combination with a bail, of elongated clamping-plates hinged thereto, one of said plates comprising an elongated body terminating in an enlarged head provided with a 90 socket, and the other having its lower end bent to form a lip to fit within said socket, and a sliding bail carrying a cam-lever to close said plates.

3. In a clasp, the combination with a bail, 95 of clamping-plates hinged thereto, one of said plates comprising an elongated body having notches running transversely thereof and ter-

minating in an enlarged head having a struck-up portion serving as a socket, and the other being elongated and having its lower end bent to form a lip to fit within said socket, a
5 sliding bail embracing said plates, and a cam-lever mounted on said bail to clamp said plates.

In testimony whereof I affix my signature in presence of two witnesses.

OTTO KEMPER.
